INVENTOR:

Edwin R. Cahoon,

BY Drake ATTY'S.

UNITED STATES PATENT OFFICE.

EDWIN R. CAHOONE, OF NEWARK, NEW JERSEY.

DESIGN FOR A BRIDLE-FRONT.

SPECIFICATION forming part of Design No. 17,400, dated June 21, 1887.

Application filed May 13, 1887. Serial No. 238,144. Term of patent 7 years.

To all whom it may concern:

Be it known that I, EDWIN R. CAHOONE, a citizen of the United States, residing at Newark, in the county of Essex and State of New Jersey, have invented and produced a new and original Design for Bridle-Fronts; and I do hereby declare the following to be a full, clear, and exact description of the invention, such as will enable others skilled in the art to which it appertains to make and use the same, reference being had to the accompanying drawings, and to letters of reference marked thereon, which form a part of this specification—

In said drawings, Figures 1 and 2 are front views of a bridle-front embracing my design, the latter showing a slight variation in the relation of parts. Fig. 3 is a plan of the said bridle-front. Fig. 4 is a section through line *x* of Fig. 2, and Fig. 5 is a sectional view taken 20 through line *Y* of Fig. 1.

The leading feature of the design consists in a bridle-front, which comprises the bridle-front with ribs *b b* at its upper and lower edges, between which are displayed ornamental spirals extending transversely across the recess from one rib to the other and displaying beneath the exposed parts of the spirals a strap-like band.

In said drawings, *a* indicates a bridle-front 30 with longitudinal ribs *b b* extending along the upper and lower edges of the same, between which is a longitudinal recess, *c*. *d* is an ornamental spiral wire displayed

within said recess along the front face of the bridle-front. The exposed portions of the individual spirals of the said wire lie a little apart, parallel with one another, extending transversely across the recess from one rib to the other, and between the same may be seen a strap-shaped band, *e*, lying near the bottom 40 of the recess, separated away from the said exposed portions. When viewed in transverse sections or endwise the spirals are shown to fill the recess or to extend from the upper rib to the lower one, and to extend or project 45 above or beyond the edges of the said ribs, the bridle-front thus being curved or oval in its general outer or front face contour, as indicated in Figs. 4 and 5.

Having thus described the invention, what I 50 claim as new is—

The design for a bridle-front, which comprises the bridle front with ribs *b b* at its upper and lower edges, between which are ornamental spirals extending transversely across 55 the recess from one rib to the other and displaying beneath the exposed parts of the spirals a strap-like band, substantially as described.

In testimony that I claim the foregoing I 60 have hereunto set my hand this 10th day of May, 1887.

EDWIN R. CAHOONE.
